Primary Examiner—Freda S. Nunn*Assistant Examiner*—Kevin K Rudzinski(74) *Attorney, Agent, or Firm*—Sughrue Mion, PLLC(57) **CLAIM**

The ornamental design for a light, as shown and described.

DESCRIPTION

FIG. 1 is a front elevational view of a light showing our new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a perspective view thereof; and,

FIG. 8 is cross sectional view thereof, taken along line 8—8 in FIG. 1.

The portions shown in broken lines are for illustrative purposes only and form no part of the claimed design.
